UNITED STATES PATENT OFFICE

JAN PIETRUSZKIEWICZ, OF KULPMONT, PENNSYLVANIA.

MAIL-BOX.

1,199,301.

Specification of Letters Patent. Patented Sept. 26, 1916.

Application filed April 13, 1916. Serial No. 90,906.

To all whom it may concern:

Be it known that I, JAN PIETRUSZKIEWICZ, a citizen of the United States, residing at Kulpmont, in the county of Northumberland and State of Pennsylvania, have invented certain new and useful Improvements in Mail-Boxes, of which the following is a specification.

This invention relates to certain new and useful improvements in mail boxes.

The primary object of the invention is the provision of a deposit box for mail having the lid thereof automatically locked upon closing the mail entrance slot whereby a person unfamiliar with the box would be unable to gain access thereto.

A further object of the device is to provide a lid lock for a receptacle engageable upon swinging the cover slide of the entrance slot to its closing position, a spring lock being also arranged for maintaining the lid closed and releasable only by an inserted key.

With these general objects in view and others that will appear as the nature of the invention is better understood, the same consists in the novel construction, combination and arrangement of parts hereinafter more fully described, illustrated in the accompanying drawings, and then claimed.

In the drawings forming a part of this application and in which like designating characters refer to corresponding parts throughout the several views:—Figure 1 is a vertical transverse sectional view through the device in its secured closed position. Fig. 2 is a top plan view thereof with the slot plate in its open position partially broken away. Fig. 3 is a sectional view taken upon line III—III of Fig. 1. Fig. 4 is a sectional view taken upon line IV—IV of Fig. 1, and, Fig. 5 is a detail horizontal sectional view taken substantially upon the same line of section as Fig. 4 and illustrating the key in its released position.

Referring more in detail to the drawings, the mail box broadly consists in a casing or receptacle 10 rectangular in cross-section having a top 11 provided with a lid 12 attached thereto by means of hinges 13, the said lid being provided with a mail entrance slot 14 positioned longitudinally therethrough. Laterally projecting ears 15 are carried by the rear wall 16 of the casing being adapted for rigidly mounting the mail box upon any desirable support.

A U-shaped keeper 17 is secured interiorly of the casing 10 upon the side wall 18 thereof being adapted for engagement by the curved edge portion of a disk 19 concentrically secured to a post 20 journaled through the lid 12 and having a cover plate 21 for the slot 14 secured to its free end projecting exteriorly of the said lid. A button 22 is preferably arranged upon the post 20 between the disk 19 and the lid 12, it being thus apparent that the disk 19 will be revolved upon shifting the plate 21. An interrupted or flattened side face 23 is provided for the disk 19, the said disk being in the same plane as the depression of the U-shaped keeper 17 when the lid 12 is closed whereby the curved edge of the disk 19 will engage within the keeper 17 when the plate 21 is shifted to cover the slot 14, as best illustrated in Fig. 1 of the drawing while the said disk will be released from the keeper 17 on account of the interruption in its periphery at the side face 23 when the plate is shifted projecting outwardly substantially perpendicular to the side edge of the lid 12 as shown in Fig. 2.

It will be thus apparent that when the lid is closed and the slot 14 is also closed, the lid will be prevented from being opened by means of the engagement of the disk 19 with the keeper 17 so that a person unfamiliar with the mail box will be ignorant as to the manner of opening the same. A snap lock is also provided for the box which is in the form of a spring latch 24 arranged within the casing 10 and having one end secured as at 25 to the front side 26 thereof. The latch 24 is angular in cross-section having a flange 27 adapted to receive a hook 28 therebeneath, the said hook being carried by the lid 12 while the latch 24 is connected to the wall 26 by means of a coil spring 29.

When the lid 12 is closed, the hook 28 is automatically engaged by the latch 24. The casing side 18 is provided with a key-hole 30 in substantial alinement with the latch 24 adapted for the reception of a suitable key 31 which is adapted to be slidably received upon an angular guide 32 carried by the wall 26 in parallelism and slightly below the latch 24. Upon inserting the key 31 through the keyhole 30 with its free inner end resting upon the guide 32, the key may be partially rotated for bringing its ward 33 in contact with the latch 24 for moving the latch outwardly against the tension of the

latch and also the spring 29, thus releasing the latch flange 27 from the hook 28 and allowing the lid 12 to be readily swung open upon its hinges 13 providing the aforementioned disk 19 is in its released position. A pivoted closure 34 is provided for the key-hole 30.

While the form of the invention herein shown and described is what is believed to be the preferred embodiment thereof, it is nevertheless to be understood that various forms, modifications and arrangements of the parts may be made without departing from the spirit and scope of the invention as claimed.

What I claim as new is:—

1. A mail box comprising a casing having a hinged lid provided with an entrance slot therethrough, a post journaled through the said lid, a cover plate for the said slot flatly engaging the outer face of the lid and having one end secured to the outwardly projecting end of the said post, a locking disk having an interrupted side face secured to the inner end of the said post, and a U-shaped keeper fixedly arranged within the casing having the depression thereof in the

same horizontal plane as the said disk when the lid is in its closed position.

2. A mail box provided with a hinged lid having an entrance slot therein, a pivoted cover plate for the said slot, a keeper within the box, and a locking disk on the inner side of the lid operatively connected to the said plate.

3. A mail box comprising a casing having a hinged lid provided with an entrance slot therethrough, a post journaled through the said lid, a cover plate for the said slot flatly engaging the outer face of the lid and having one end secured to the outwardly projecting end of the said post, a locking disk having an interrupted side face secured to the inner end of the said post, a U-shaped keeper fixedly arranged within the casing having the depression thereof in the same horizontal plane as the said disk when the lid is in its closed position, and a key releasable spring latch for the said lid arranged upon the adjacent side of the casing with respect to the said keeper.

In testimony whereof I affix my signature.

JAN PIETRUSZKIEWICZ.
